RECORDING DEVICE AND RECORDING METHOD

The present application is based on, and claims priority from JP Application Serial Number 2021-125498, filed Jul. 30, 2021, the disclosure of which is hereby incorporated by reference herein in its entirety.

BACKGROUND

1. Technical Field

The present disclosure relates to a recording device configured to perform recording by ejecting liquid to a recording medium, and a recording method performed by the recording device.

2. Related Art

In an inkjet printer that ejects ink to a medium, there has been known a configuration that includes a roller configured to transport a medium further downstream by rotating while coming into contact with the medium, on a downstream side of a head that ejects ink in a transport direction. When the roller is in contact with the medium after recording, a problem may occur where a portion of the ink on the medium sticks to the roller, and the ink sticking to the roller is transferred to the medium, as a result, the medium is stained.

There has been disclosed a recording device in which a sheet ejecting roller and a transport spur are disposed downstream of a recording head and a platen in a transport direction (see, JP-A-2014-141027). According to JP-A-2014-141027, a sheet after recording is transported along the transport direction in a state where the sheet is sandwiched between the sheet ejecting roller and the transport spur. A tooth portion is formed on a periphery of the transport spur and hence, a contact area of the transport spur with a surface of a sheet on which recording is performed is small. Accordingly, it is possible to suppress the transfer, to the sheet, of the ink sticking to a rotating body for transporting the sheet to some extent.

It is necessary to prevent deterioration of recording quality caused by sticking of the ink to the roller. In view of the above, there is a demand for a technique that serves to detect an effect on a recording result attributed to sticking of ink to the roller. Further, in the configuration disclosed JP-A-2014-141027, there is a concern that an indentation generated by biting of the tooth portion of the spur into the medium affects the recording quality.

SUMMARY

A recording device including: a liquid ejecting unit configured to eject liquid to a first surface of a medium transported in a transport direction, a roller disposed downstream of the liquid ejecting unit in the transport direction and configured to rotate in contact with the first surface, and a control unit, wherein the control unit is configured to form a first pattern of the liquid on the first surface by controlling ejection of the liquid by the liquid ejecting unit, and to form a detection region for the first pattern at a specific position on the first surface at which the roller is brought into contact with the first surface when a rotational angle of the roller becomes $m^{\circ} + 360^{\circ}$, m° being a rotational angle of the roller when the roller is brought into contact with the first pattern.

A recording method performed by a recording device that includes: a liquid ejecting unit configured to eject liquid to a first surface of a medium transported in a transport direction, and a roller disposed downstream of the liquid ejecting unit in the transport direction and configured to rotate in contact with the first surface, wherein the method comprising a pattern forming step in which a first pattern of the liquid is formed on the first surface by the liquid ejecting unit, and a detection region for the first pattern is formed at a specific position on the first surface at which the roller is brought into contact with the first surface when a rotational angle of the roller becomes $m^{\circ} + 360^{\circ}$, m° being a rotational angle of the roller when the roller is brought into contact with the first pattern.

BRIEF DESCRIPTION OF THE DRAWINGS

FIG. 1 is a block diagram illustrating a configuration of a device according to a present embodiment in a simplified manner.

FIG. 2 is a view illustrating the relationship and the like between a recording head and a medium and the like in a simplified manner as viewed in a width direction.

FIG. 3 is a view illustrating the relationship and the like between the recording head and the medium in a simplified manner as viewed from above.

FIG. 4 is a view illustrating a stain detection pattern of a first example.

FIG. 5 is a view illustrating a stain detection pattern of a second example.

FIG. 6 is a view illustrating a stain detection pattern of a third example.

FIG. 7 is a view illustrating a stain detection pattern of a fourth example.

DESCRIPTION OF EXEMPLARY EMBODIMENTS

Embodiments of the present disclosure will be described below with reference to respective drawings. Here, each of the drawings is merely illustrative for describing the present embodiment. Since the respective drawings are illustrative, proportions and shapes of the constitutional elements may not be precise or may not match each other and, further, may be partially omitted.

1. Schematic Description of Device:

FIG. 1 illustrates a configuration of a recording device 10 according to a present embodiment, in a simplified manner. The recording device 10 is provided with a control unit 11, a display unit 13, an operation receiving unit 14, a communication IF 15, a transport unit 16, a recording head 17, and the like. IF is an abbreviation for interface. A recording method is implemented by the recording device 10.

The control unit 11 is configured to include, as a processor, one or a plurality of ICs including a CPU 11a, a ROM 11b, a RAM 11c, and the like, other non-volatile memories, and the like. In the control unit 11, the processor, that is, the CPU 11a executes arithmetic processing in accordance with a program 12 stored in the ROM 11b, other memories, or the like, using the RAM 11c or the like as a work area. By following the program 12, the control unit 11 realizes a plurality of functions such as a pattern forming unit 12a, an input amount setting unit 12b, and the like. The processor is not limited to the single CPU, and a configuration may be adopted in which the processing is performed by a plurality of CPUs, a hardware circuit such as an ASIC, or the like, or

a configuration may be adopted in which the CPU and the hardware circuit perform the processing in corporation with each other.

The display unit 13 is a unit for displaying visual information, and is constituted, for example, of a liquid crystal display, an organic EL display, or the like. The display unit 13 may be configured to include a display and a driving circuit for driving the display. The operation receiving unit 14 is a device for receiving an operation by a user, and is realized, for example, by a physical button, a touch panel, a mouse, a keyboard, or the like. As a matter of course, the touch panel may be realized as a function of the display unit 13. The display unit 13 and the operation receiving unit 14 may also be collectively referred to as an operating panel of the recording device 10.

The display unit 13 and the operation receiving unit 14 may be a part of the configuration of the recording device 10, or may be peripheral equipment externally mounted on the recording device 10.

The communication IF 15 is a generic term for one or a plurality of IFs for executing the communication between the recording device 10 and the outside in a wired or wireless manner, in accordance with a predetermined communication protocol including a known communication standard. The control unit 11 is configured to communicate with a personal computer, a server, a smartphone, a tablet type terminal, or the like, that is not illustrated in the drawing, via the communication IF 15, for example.

The transport unit 16 is a unit for transporting a sheet-shaped medium along a predetermined transport direction under the control by the control unit 11, and includes a roller configured to rotate to transport a medium, a motor for driving the roller, and the like. Although the medium is typically paper, the medium may be a medium made of a material other than paper provided that recording by liquid can be performed.

The recording head 17 has a plurality of nozzles not illustrated in the drawing, is configured to eject liquid such as ink from the respective nozzles to a medium transported by the transport unit 16 under the control by the control unit 11. The recording head 17 corresponds to a "liquid ejecting unit". The recording head 17 may be referred to as a liquid ejecting head, a printing head, a printing head, an inkjet head, or the like. A liquid droplet that the recording head 17 ejects from the nozzle is also referred to as a dot.

It is known that the recording device 10 is configured to eject or not eject dots from the respective nozzles by controlling the application of drive signals to drive elements not illustrated in the drawing that the respective nozzles include in accordance with recording data. The recording head 17 is configured to perform recording by ejecting, for example, inks of respective colors, such as cyan (C), magenta (M), yellow (Y), and black (K), inks of colors other than these colors, and liquid other than the inks.

FIG. 2 illustrates the relationship and the like between the recording head 17 and a medium 30 in a simplified manner as viewed in a width direction intersecting with a transport direction D1. In this specification, intersection between the transport direction D1 and the width direction means that the transport direction D1 and the width direction are orthogonal or nearly orthogonal to each other. A side upstream in the transport direction D1 and a side downstream in the transport direction D1 are simply referred to as an upstream side and a downstream side. In FIG. 3 described later, the width direction is indicated as a width direction D2. Symbol 19 indicates a platen 19 serving as a part of a transport path of the medium 30. The platen 19 supports the medium 30

transported along the transport direction D1 from below. The recording head 17 is supported at a position above the platen 19 so as to face the platen 19.

A first roller pair formed of a first roller 16a and a second roller 16b is disposed upstream of the recording head 17. Further, a second roller pair formed of a third roller 16c and a fourth roller 16d is disposed downstream of the recording head 17. These roller pairs are a part of the transport unit 16. Each roller pair is configured to transport the medium 30 by rotating in a state where the medium 30 is sandwiched between rollers provided in pair. The rollers included in the transport unit 16 are not limited to the rollers illustrated in the drawing.

A lower surface of the recording head 17 that faces the platen 19 is a nozzle surface 18 where the plurality of nozzles open, and the ink is ejected to the medium 30 that is supported by the platen 19 from respective nozzles that open at the nozzle surface 18. As can be understood from FIG. 2, the recording is performed by ejecting ink to a first surface 30a out of the first surface 30a and a second surface 30b of the medium 30, the first surface 30a faces the nozzle surface 18, and the second surface 30b is a back surface of the first surface 30a. Accordingly, in an example illustrated in FIG. 2, the third roller 16c constituting the second roller pair corresponds to "a roller disposed downstream of the liquid ejecting unit and rotating in contact with the first surface 30a".

FIG. 3 illustrates the relationship and the like between the recording head 17 and the medium 30 in a simplified manner as viewed from above. In FIG. 3, the illustration of the platen 19 is omitted. Although not illustrated in FIG. 1 and FIG. 2, in an example illustrated in FIG. 3, the recording head 17 is mounted on a carriage 20. The carriage 20 is movable in a reciprocating manner along the width direction D2 by receiving power from a motor. That is, the recording head 17 ejects ink while moving along the width direction D2 together with the carriage 20, so that the recording on the first surface 30a of the medium 30 is performed. The control unit 11 alternately executes the ejection of ink from the recording head 17 accompanying with the movement of the carriage 20, and the transport of a predetermined distance of the medium 30 by the transport unit 16 thus performing the recording on the medium 30.

However, the configuration in which the recording head 17 is moved by the carriage 20 is not essential. For example, the recording head 17 may be configured to be fixed while having a length over a length (medium width) of the medium 30 in the width direction D2, and to perform the recording by ejecting ink to the medium 30 that is transported downstream at a predetermined speed.

In the example illustrated in FIG. 3, a plurality of first rollers 16a located upstream of the recording head 17 are provided along the width direction D2. All of the plurality of first rollers 16a have the same function, and it may be construed that the plurality of first rollers 16a rotate in synchronization. In the same manner, in the example illustrated in FIG. 3, a plurality of third rollers 16c located downstream of the recording head 17 are provided along the width direction D2. All of the plurality of third rollers 16c have the same function, and it may be construed that the plurality of third rollers 16c rotate in synchronization. Although not illustrated in FIG. 3, as a matter of course, a plurality of second rollers 16b are provided at respective positions corresponding to the plurality of first rollers 16a and below the medium 30. In the same manner, although not illustrated in FIG. 3, a plurality of fourth rollers 16d are

provided at respective positions corresponding to the plurality of third rollers **16c** and below the medium **30**.

The printing device **10** may be realized not only by an independent single printer, or may be realized by a plurality of devices communicably coupled to each other. For example, the recording device **10** may be realized by a system that includes an information processing device including the control unit **11**, and a printer including the transport unit **16** and the recording head **17**. The recording device **10** may be referred to as a liquid ejection device, a printing apparatus, an inkjet printer, or the like.

2. Pattern Formation:

Next, the pattern forming step according to the present embodiment is described. In the pattern forming step, the control unit **11** forms a “first pattern” by liquid on the first surface **30a** of the medium **30** by controlling the ejection of liquid by the recording head **17**, and forms a “detection region” for the first pattern at a specific position on the first surface **30a** at which the third roller **16c** is brought into contact when a rotational angle of the third roller **16c** becomes $m^\circ + 360^\circ$ with respect to a rotational angle m° of the third roller **16c** when the third roller **16c** is brought into contact with the first pattern. That is, in the pattern forming step, at least the first pattern and the detection region are formed on the first surface **30a**.

Here, “a specific position with which the third roller **16c** is brought into contact when the rotation angle of the third roller **16c** becomes $m^\circ + 360^\circ$ with respect to the rotational angle m° of the third roller **16c** when the third roller **16c** is brought into contact with the first pattern” can be paraphrased as a position with which the third roller **16c** is brought into contact when the third roller **16c** is rotated by one turn from a state in which the third roller **16c** is brought into contact with the first pattern. Accordingly, in practice, what is used as reference for determining the rotational angle m° , and a type of rotational angle m° are not important. Further, the rotation of the roller described in this specification is a rotation for transporting the medium **30** downstream and hence, the detection region is located upstream of the first pattern corresponding to the detection region.

Hereinafter, the pattern including the first pattern and the detection region is referred to as “stain detection pattern”. The pattern forming unit **12a** of the control unit **11** records a stain detection pattern on the first surface **30a** of the medium **30** based on recording data of a stain detection pattern preliminarily stored in a predetermined memory, by controlling the recording head **17** and the transport unit **16**.

First Example

FIG. 4 illustrates a stain detection pattern **40** according to the first example recorded on the first surface **30a** of the medium **30** by the pattern forming step. In FIG. 4, a correspondence relationship between the medium **30** and the directions **D1** and **D2** is also illustrated. In the stain detection pattern **40**, a plurality of first patterns **31a**, **31b**, **31c**, **31d**, and **31e** are formed so as to be arranged apart from each other in the transport direction **D1**. It may be construed that each of the first patterns **31a**, **31b**, **31c**, **31d**, and **31e** is a rectangular matted pattern elongated in the width direction **D2**, and all of the first patterns have the same size. It may be construed that the matted pattern is, for example, a pattern in which dots of the ink are disposed uniformly or substantially uniformly, so that there is no gradation or substantially no gradation within the pattern.

A length of the first pattern in the transport direction **D1** is set as **H**. In the transport direction **D1**, a length in the transport directional of a region, secured between the first pattern and the first pattern in the transport direction **D1**, is also set as **H**. Here, in the first example, the relationship $H=A/n$ is established, wherein **A** is a circumference of the third roller **16c**.

n is a positive integer, and is suitably an odd number. In the first example, **n** is set to 3 (**n=3**). Since the circumference **A** is already known on the design of a product, the pattern forming unit **12a** records the stain detection pattern **40** on the medium **30** while assuming one third of the circumference **A** as the length **H**.

A distance of $H \times 3$ in the transport direction **D1** on the medium **30** corresponds to a distance of one rotation of the third roller **16c**. Therefore, according to FIG. 4, when the first pattern **31a** is assumed as the reference, a region adjacent to an upstream side of the first pattern **31b** is a specific position, and this specific position is a detection region **32a** for the first pattern **31a**. That is, when the ink of the first pattern **31a** sticks to the third roller **16c**, the ink is transferred to the detection region **32a** due to one rotation of the third roller **16c**. Accordingly, it is possible to determine whether the concentration of the first pattern **31a** is appropriate on the recording quality by detecting the stain in the detection region **32a**.

In this manner, the detection region for the first pattern is a region for detecting the transfer of the ink of the first pattern.

In the same manner, when the first pattern **31b** is assumed as the reference, a region adjacent to an upstream side of the first pattern **31c** is a specific position, and this specific position is a detection region **32b** for the first pattern **31b**.

When the first pattern **31c** is assumed as the reference, a region adjacent to an upstream side of the first pattern **31d** is a specific position, and this specific position is a detection region **32c** for the first pattern **31c**. When the first pattern **31d** is assumed as the reference, a region adjacent to an upstream side of the first pattern **31e** is a specific position, and this specific position is a detection region **32d** for the first pattern **31d**. When the first pattern **31e** is assumed as the reference, a region located away from the first pattern **31e** by a distance $H \times 3$ toward an upstream side is a specific position, and the specific position is a detection region **32e** for the first pattern **31e**.

According to the first example, the detection regions **32a**, **32b**, **32c**, **32d**, and **32e** are “non-recording region” where liquid is not ejected from the recording head **17**. The non-recording region is, per se, the surface of the medium **30**, and is also referred to as “blank region”. By setting the detection region as the blank region, the presence or absence of transfer of the ink of the first pattern and the degree of transfer of the ink can be easily detected. In the present embodiment, “ensuring of the blank region as the detection region between the first patterns” is also referred to as “forming of the detection region”.

In FIG. 4, each of the detection regions **32a**, **32b**, **32c**, **32d**, and **32e** is illustrated by being surrounded by a broken-line frame for making it easy to see, but such a frame may be present or may not be present in an actual stain detection pattern **40**.

As can be understood from FIG. 4, the plurality of first patterns **31a**, **31b**, **31c**, **31d**, and **31e** are different from each other in concentration. By recording the plurality of first patterns **31a**, **31b**, **31c**, **31d**, and **31e** that are different from each other in concentration, it is possible to determine the

concentration at which a stain attributed to sticking of ink to the third roller **16c** is not generated.

Further, as can be understood from FIG. 4, the pattern forming unit **12a** forms the plurality of first patterns **31a**, **31b**, **31c**, **31d**, and **31e** such that the concentrations of the first patterns are increased in a stepwise manner from the downstream side to the upstream side. According to FIG. 4, among the plurality of first patterns **31a**, **31b**, **31c**, **31d**, and **31e**, the first pattern **31a** on the most downstream side has the lowest concentration, and the first pattern **31e** located most upstream has the highest concentration. When the high-concentration first pattern is recorded prior to the low-concentration first pattern, there is a concern that the ink sticking to the third roller **16c** from the high-concentration first pattern partially remains on the third roller **16c** even after the ink is transferred to the corresponding detection region so that the remaining ink affects the detection of a stain relating to other first patterns. In view of the above, in order to avoid such a problem, a plurality of first patterns are formed such that the concentrations of the first patterns are increased in a stepwise manner from the downstream side to the upstream side.

Recording data that the pattern forming unit **12a** uses for recording the stain detection pattern **40**, of course, defines a different concentration with respect to each of the first patterns **31a**, **31b**, **31c**, **31d**, and **31e**. In a state of the recording data, one first pattern is expressed as a set region of pixels having the same concentration. Each pixel constituting the recording data has, for example, a gradation value for each color of CMYK. The gradation value is a value expressed by 256 gradations, that is, 0 to 255, for example, and 0 corresponds to the concentration of 0%, and 255 corresponds to the concentration of 100%. Accordingly, the pixel may take a concentration of 400% at maximum when the gradation values of the CMYK are added to each other.

In the first example, all of the first patterns **31a**, **31b**, **31c**, **31d**, and **31e** are patterns that are recorded by mixing CMYK inks. Accordingly, the concentration of the first pattern is the density of the pixels constituting the first pattern in the recording data. As a matter of course, the pattern forming unit **12a** performs a so-called halftone processing or the like on the recording data thus converting the recording data into data in which dot ejection (dot on) or dot non-ejection (dot off) is defined for each pixel and each ink color. Thereafter, the pattern forming unit **12a** supplies the converted data to the recording head **17** thus causing the recording head **17** to record the stain detection pattern **40**.

The pattern forming unit **12a** records the stain detection pattern **40** on the medium **30** in a state where the plurality of first patterns **31a**, **31b**, **31c**, **31d**, and **31e** include the first pattern whose concentration is set to a preset maximum value. In FIG. 4, the first pattern **31e** located most upstream corresponds to the first pattern whose concentration is set to the maximum value. In this specification, the maximum value of the concentration is a concentration that can be realized by the recording head **17**, and is a concentration set by taking into account characteristics of ink such as blurring of ink on the medium **30**. As in the case of the above-mentioned example, when the recording head **17** can perform color printing by mixing inks of colors of CMYK, the pixel of the recording data can take a concentration of 400% at maximum. However, the maximum value of the concentration in this specification is set to a value lower than 400% such as 300% or 250%, for example.

According to the first example described above, the pattern forming unit **12a** forms a plurality of first patterns side by side in the transport direction **D1** in a region having

a length corresponding to the circumference of the third roller **16c** in the transport direction **D1** of the medium **30**. Here, the plurality of first patterns each have a length **H**, in the transport direction **D1**, corresponding to a value obtained by dividing the circumference by a positive integer **n**, and the plurality of first patterns are different from each other in concentration. For example, the first pattern **31a** and the first pattern **31b** are formed in a region having a length corresponding to the circumference of the third roller **16c** on the first surface **30a**. The pattern forming unit **12a** forms a detection region having a length in the transport direction **D1** corresponding to the length **H** of the first pattern at each of a plurality of specific positions respectively corresponding to the plurality of first patterns. "The length of the transport direction **D1** corresponds to the length **H** of the first pattern" means that the length in the transport direction **D1** is equal to or substantially equal to the length **H** of the first pattern. In this manner, by disposing the plurality of first patterns in the region having the length corresponding to the circumference of the third roller **16c**, the stain detection pattern can be made compact and hence, it is possible to contribute to the suppression of medium consumption and the reduction of reading time of the pattern.

According to FIG. 4, the detection region **32d** for the first pattern **31d** and the detection region **32e** for the first pattern **31e** are located upstream of the first pattern **31e** located most upstream, and are not sandwiched between the first patterns respectively. Further, in the first example, the first pattern is the blank region. Accordingly, it is difficult for a user to grasp positions of the detection region **32d** and the detection region **32e** on the medium **30**. In view of such circumstances, the pattern forming unit **12a** may be configured to form the third pattern **33** in a region between the detection region **32e** located most upstream in the transport direction **D1** of the first surface **30a** and the detection region **32d** located second most upstream succeeding to the detection region **32e** located most upstream by causing the recording head **17** to eject ink.

That is, the pattern forming unit **12a** may be configured to record the stain detection pattern **40** including the third pattern **33** on the first surface **30a** of the medium **30**. In FIG. 4, for the sake of convenience, the third pattern **33** is indicated by hatching for distinguishing the third pattern **33** and the first patterns **31a**, **31b**, **31c**, **31d**, and **31e** from each other. By recording the third pattern **33**, the user can easily grasp positions of the detection region **32d** and the detection region **32e** that are the blank regions. Here, the third pattern **33** does not need to be a matted pattern, provided that the third pattern **33** consequently functions as a mark for facilitating grasping of the positions of the detection region **32d** and the detection region **32e**, the third pattern **33** may have any color, pattern, and shape.

3. Treatment after Pattern Forming Step:

After the pattern forming step, a stain detection step and an injection amount setting step are performed. The stain detection step and the injection amount setting step are briefly described.

In the stain detection step, a stain attributed to transfer of the ink is detected by reading the first surface **30a** of the medium **30** on which the stain detection pattern is recorded by the recording device **10**. As a matter of course, the medium **30** on which the stain detection pattern is recorded by the recording device **10** is the medium **30** discharged by the transport by the transport unit **16** after recording by the recording head **17**. Accordingly, there is a possibility that a stain is generated on the medium **30** due to sticking of the ink to the third roller **16c**. The stain detection step may be

a step where a person visually detects the stain, or may be a step where the detection is performed using a reading apparatus such as a scanner or a colorimeter. In the stain detection step, for example, a user detects the degree of stain in the detection region by visual confirmation. Alternatively, in the stain detection step, for example, the scanner reads the first surface **30a** of the medium **30**, and detects the degree of stain by comparing the degree of stain in the detection region in the reading data with a predetermined threshold, or the like.

In the injection amount setting step, the injection amount setting unit **12b** of the control unit **11** acquires a detection result of the stain detection step. For example, when the user inputs the detection result by operating the operation receiving unit **14**, the injection amount setting unit **12b** can acquire the detection result. Alternatively, the injection amount setting unit **12b** can acquire the detection result from the scanner or the like coupled to the recording device **10**. Alternatively, the injection amount setting unit **12b** may be configured to input the reading data of the first surface **30a** of the medium **30** from the scanner or the like, analyze the reading data, and acquire the degree of stain of the detection region as a detection result.

The injection amount setting unit **12b** sets an injection amount (ejection amount) of ink corresponding to the acquired detection result. Assume that the injection amount setting unit **12b** acquires a detection result that there is no stain of ink in the detection regions **32a**, **32b**, and **32c**, and there is a stain attributed to ink in the detection regions **32d**, **32e**, for example. In this case, when a concentration equal to or more than the concentration of the first pattern **31d** is adopted, the lowering of recording quality such as a stain attributed to sticking of ink to the third roller **16c** occurs. Accordingly, for example, the injection amount setting unit **12b** sets an upper limit of a concentration that can be taken by the recording data for driving the recording head **17** to a concentration of the first pattern **31c** or a concentration equal to or more than the concentration of the first pattern **31c** and less than the concentration of the first pattern **31d** and, thereafter, such setting is applied in recording various images that the user wants to record. As a result, a stain of the medium by the ink caused by sticking of the ink to the third roller **16c** can be eliminated. Further, the upper limit of the injection amount of ink by the recording head **17** is not required to be lower than necessary and hence, the lowering of color developing property of the recording result can be suppressed so that the recording quality can be maintained.

4. Other Examples

Second Example

FIG. 5 illustrates a stain detection pattern **41** according to the second example recorded on the first surface **30a** of the medium **30** by the pattern forming step. In the second example, and third and fourth examples described below, a point that makes a stain detection pattern **41**, **42**, **43** different from the stain detection pattern **40** of the first example will be described.

The detection region may not be a non-recording region (blank region) but may be a second pattern formed by ejecting ink. That is, the pattern forming unit **12a** may be configured to record the stain detection pattern **41** including a first pattern and a second pattern on the first surface **30a** based on the recording data of the stain detection pattern **41** by controlling the recording head **17** and the transport unit **16**. In the example illustrated in FIG. 5, the detection region

32a for the first pattern **31a** is a second pattern **34a**. In the same manner, the detection region **32b** for the first pattern **31b** is a second pattern **34b**, the detection region **32c** for the first pattern **31c** is a second pattern **34c**, the detection region **32d** for the first pattern **31d** is a second pattern **34d**, and the detection region **32e** for the first pattern **31e** is a second pattern **34e**.

In FIG. 5, for the sake of convenience, in order to distinguish the first patterns **31a**, **31b**, **31c**, **31d**, and **31e** and the second patterns **34a**, **34b**, **34c**, **34d**, and **34e** from each other, the second patterns **34a**, **34b**, **34c**, **34d**, and **34e** are indicated by hatching that is different from the one applied to the third pattern **33**. The detection region is a region for detecting the presence or absence of sticking of ink of the first pattern and the degree of sticking of ink and hence, even when the first patterns **31a**, **31b**, **31c**, **31d**, and **31e** are formed in any color, the pattern forming unit **12a** forms the second patterns **34a**, **34b**, **34c**, **34d**, and **34e** in different color from that of the first patterns **31a**, **31b**, **31c**, **31d**, and **31e**.

In order to make sticking of ink of the first patterns **31a**, **31b**, **31c**, **31d**, and **31e** conspicuous, for example, the pattern forming unit **12a** may form the second patterns **34a**, **34b**, **34c**, **34d**, and **34e** in color having the lower concentration than that of the first patterns **31a**, **31b**, **31c**, **31d**, and **31e**.

Further, in order to make sticking of ink of the first patterns **31a**, **31b**, **31c**, **31d**, and **31e** conspicuous, for example, the pattern forming unit **12a** may form the second patterns **34a**, **34b**, **34c**, **34d**, and **34e** in color corresponding to color complementary to the color of the first patterns **31a**, **34b**, **34c**, **34d**, and **31e**.

When the medium **30** is formed of a transparent film, the recording device **10** forms a base on the transparent film using a white ink, and performs recording on the base using other color inks such as inks of CMYK. Here, the pattern forming unit **12a** may be configured to form the second patterns **34a**, **34b**, **34c**, **34d**, and **34e** using the white ink by causing the recording head **17** to eject the white ink. That is, unlike the case of the first example in which the detection region is formed in the color of the medium **30** per se, a configuration may be adopted where, by forming the detection region using a white image formed using the white ink, the transfer of the ink from the first pattern can be more clearly recognized. As a matter of course, whether or not the medium **30** is formed of a transparent film, the detection region can be formed of a white image using the white ink.

Although not illustrated in FIG. 5, the stain detection pattern **41** may include the third pattern **33** in the same manner as the stain detection pattern **40**.

Third Example

FIG. 6 illustrates a stain detection pattern **42** according to the third example recorded on the first surface **30a** of the medium **30** by the pattern forming step.

The first pattern is recorded for contacting with the third roller **16c**. In other words, it is not necessary to record the first pattern at a position that does not contact with the third roller **16c**. As illustrated in FIG. 3, the plurality of third rollers **16c** are disposed in a spaced apart manner in the width direction **D2** at a downstream position of the recording head **17**.

Accordingly, the pattern forming unit **12a** may be configured to record the stain detection pattern **42** on the first surface **30a** by controlling the recording head **17** such that the first pattern is positioned corresponding to a plurality of predetermined positions at which the third rollers **16c** exist in the width direction **D2**. When the stain detection pattern

11

42 is compared with the stain detection pattern 40, the stain detection pattern 42 differs from the stain detection pattern 40 with respect to a point that the first patterns 31a, 31b, 31c, 31d, and 31e and the detection regions 32a, 32b, 32c, 32d, and 32e are respectively formed in a spaced apart manner in the width direction D2 corresponding to the plurality of predetermined positions at which the third rollers 16c exist. As a matter of course, also in the third example, the detection regions 32a, 32b, 32c, 32d, and 32e may not be formed of a blank region, and may be formed of a second pattern. In this manner, by recording the first pattern corresponding to the plurality of predetermined positions at which the third rollers 16c exist in the width direction D2, the consumption of ink can be suppressed in performing recording of the stain detection pattern.

Further, the pattern forming unit 12a may be configured such that the recording head 17 records the indication of concentrations of the first patterns 31a, 31b, 31c, 31d, and 31e in a region on the first surface 30a avoiding the first patterns 31a, 31b, 31c, 31d, and 31e in the width direction D2, together with the recording of the first patterns 31a, 31b, 31c, 31d, and 31e. "The region avoiding the first pattern in the width direction D2" means a region where the first pattern is not recorded, and means a region adjacent to the first pattern in the width direction D2.

In the example illustrated in FIG. 6, concentrations of the respective first patterns 31a, 31b, 31c, 31d, and 31e are recorded in the region avoiding the first patterns 31a, 31b, 31c, 31d, and 31e in the width direction D2 in numbers such as, for example, 100%, 150%, 200%, 250%, and 300%. These concentrations are values defined as the concentrations of the respective first patterns 31a, 31b, 31c, 31d, and 31e in the recording data of the stain detection pattern. Since such concentrations are recorded on the first surface 30a, the user can recognize the concentration of the first pattern more directly.

As a matter of course, also in the first example and the second example, the pattern forming unit 12a may be configured to record such an indication of the concentration on the first surface 30a together with the first pattern.

Fourth Example

FIG. 7 illustrates a stain detection pattern 43 according to the fourth example recorded on the first surface 30a of the medium 30 by the pattern forming step.

The pattern forming unit 12a may be configured to form, side by side, a plurality of first patterns that are different from each other in concentration in the width direction D2 by controlling the recording head 17. According to the stain detection pattern 43, although the first patterns 31a, 31b, and 31c are aligned in a spaced apart manner along the transport direction D1 as described above, the first pattern 31d is aligned with the first pattern 31a in the width direction D2, and the first pattern 31e is aligned with the first pattern 31b in the width direction D2. Also in the stain detection pattern 43, the relative positional relationship between the first pattern 31d and the detection region 32d for the first pattern 31d, and the relative positional relationship between the first pattern 31e and the detection region 32e for the first pattern 31e are as described above.

In this manner, by forming, side by side, the plurality of first patterns that are different from each other in concentration in the width direction D2, the consumption of the medium 30 required to record the stain detection pattern can be suppressed. As a matter of course, also in the fourth example, the pattern forming unit 12a may be configured to

12

form the detection regions 32a, 32b, 32c, 32d, and 32e by not the blank region but the second pattern, and to record the indication of the concentration on the first surface 30a together with the first pattern.

5. Summary:

In this manner, according to the present embodiment, the recording device 10 includes the liquid ejecting unit configured to eject liquid to the first surface 30a of the medium 30 transported in the transport direction D1, the roller (the third roller 16c) that is disposed downstream of the liquid ejecting unit in the transport direction D1 and configured to rotate in contact with the first surface 30a, and the controller 11. The control unit 11 is configured to form the first pattern of the liquid on the first surface 30a by controlling ejection of the liquid by the liquid ejecting unit, and to form a detection region for the first pattern at a specific position on the first surface 30a with which the roller is brought into contact when a rotational angle of the roller becomes m °+360°, m ° being a rotational angle of the roller when the roller is brought into contact with the first pattern.

According to the configuration described above, when the liquid ejected to the first surface 30a for forming the first pattern sticks to the roller, the liquid sticking to the roller is transferred to the detection region when the roller is rotated by one turn. Accordingly, by detecting a stain in the detection region, it is possible to detect the effect of sticking of the liquid to the roller on the recording result. Further, by utilizing this detection result, the ejection amount of the liquid by the liquid ejecting unit can be easily set to an appropriate value. Further, by detecting the stain in the detection region, it is possible to make the setting such that such a stain does not occur and hence, it is not necessary to adopt a configuration, as disclosed in JP-A-2014-141027, in which an indentation is generated by biting of a tooth portion of a spur into a medium.

Further, according to the present embodiment, the control unit 11 may be configured such that the liquid ejecting unit records the indication of the concentration of the first pattern in the region of the first surface 30a avoiding the first pattern in the width direction D2 that intersects with the transport direction D1.

According to the configuration described above, since the indication of the concentration of the first pattern is recorded by using the region adjacent to the first pattern in the width direction D2, the user can easily recognize the concentration of the first pattern.

Although it may be construed that the region for recording the indication of the concentration of the first pattern is, basically, a part of the blank region, for example, the region may be a region in which a base is recorded using a white ink or the like in order to make the characters for displaying the concentration conspicuous.

Further, according to the present embodiment, the control unit 11 may be configured to form, side by side, a plurality of first patterns that are different from each other in concentration in the width direction D2.

According to the configuration described above, the plurality of first patterns can be recorded in a smaller area compared to a case where a plurality of first patterns that are different from each other in concentration are formed side by side only in the transport direction D1 and hence, the consumption of the medium 30 can be suppressed.

Further, according to the present embodiment, the detection region may be a non-recording region in which liquid is not ejected from the liquid ejecting unit.

According to the configuration described above, by forming the detection region by the non-recording region, that is, the blank region, the stain in the detection region can be detected more easily.

Further, according to the present embodiment, the second pattern is formed in the detection region in color corresponding to a color complementary to a color of the first pattern by the liquid ejecting unit.

According to the configuration described above, by forming the detection region by the second pattern of the color complementary to the color of the first pattern, the stain in the detection region can be detected more easily.

Further, according to the present embodiment, the control unit 11 is configured to form the plurality of first patterns side by side in the transport direction D1 in a region having a length corresponding to the circumference A of the roller in the transport direction D1 of the medium 30, the plurality of first patterns each having a length H, in the transport direction D1, corresponding to a value obtained by dividing the circumference A by a positive integer n, and the plurality of first patterns being different from each other in concentration, and to form the detection region having a length in the transport direction D1 corresponding to the length H of the first pattern at each of a plurality of the specific positions respectively corresponding to the plurality of first patterns.

According to the configuration described above, the plurality of first patterns can be recorded in a smaller area compared to a case where the plurality of first patterns that are different from each other in concentration are formed side by side in the transport direction D1 and hence, the consumption of the medium 30 can be suppressed.

Further, according to the present embodiment, the integer n may be an odd number.

By setting the integer n to be an odd number, for example, 3 or 5, the first pattern and the detection region can be alternately disposed in a region having a length corresponding to the circumference A of the roller in the transport direction D1 of the medium 30.

However, the disclosure of this embodiment does not deny that an integer n is an even number. For example, it may be adopted a configuration where the length H is set to A/4 (H=A/4), a first pattern in which a length in the transport direction D1 is set to H is formed on the first surface 30a, and a detection region in which a length in the transport direction D1 is set to H is formed at a specific position that uses the first pattern as the reference.

Further, a configuration is also conceivable where only one first pattern is formed in a region having a length corresponding to the circumference A in the transport direction D1 of the medium 30. That is, it may be adopted a configuration where the length H is set to A (H=A), a first pattern in which a length in the transport direction D1 is set to H is formed on the first surface 30a, and a detection region in which a length in the transport direction D1 is set to H is formed at a specific position that uses the first pattern as the reference.

Further, according to the present embodiment, the control unit 11 may be configured to form the plurality of the first patterns such that the concentrations of the first patterns are increased in a stepwise manner from the downstream side to the upstream side in the transport direction D1.

According to the configuration, it is possible to avoid the occurrence of a phenomenon that even after the ink sticking to the roller from the first pattern having the high concentration is transferred to the corresponding detection region, the ink is transferred to other first patterns and other detection regions thus adversely affecting the detection of the stain.

Further, according to the present embodiment, the control unit 11 may be configured to include the first pattern in which the concentration is set to a preset maximum value among the plurality of the first patterns.

According to the configuration described above, by including the first pattern in which the concentration is set to the preset maximum value in the plurality of first patterns, it is possible to verify whether it is appropriate to adopt the concentration of the maximum value to the recording based on the stain in the detection region.

Further, according to the present embodiment, the control unit 11 may be configured to form the third pattern 33 in a region between the detection region located most upstream in the transport direction D1 of the first surface 30a and the detection region located second most upstream succeeding to the detection region located most upstream by controlling ejection of the liquid by the liquid ejecting unit.

According to the configuration described above, the user can easily recognize a position of the detection region located most upstream and a position of the detection region located second most upstream succeeding to the detection region located most upstream by using the third pattern 33 as a mark.

Further, according to the present embodiment, the first patterns 31a, 31b, 31c, 31d, and 31e may not be a pattern that is recorded by mixing CMYK inks but may be a pattern recorded by single-color ink.

According to the configuration described above, in recording by the single-color ink, a stain on the medium by the ink attributed to sticking of the ink to the third roller 16c can be detected, and setting for eliminating such a stain can be made.

The present embodiment is not limited to a recording device and a system, and discloses inventions of various categories such as a method that the recording device or the system performs, and the program 12 that causes the processor to execute the method. For example, the recording method performed by the recording device 10 that includes: the liquid ejecting unit configured to eject liquid to the first surface 30a of the medium 30 transported in the transport direction D1, and the roller (third roller 16c) disposed downstream of the liquid ejecting unit in the transport direction D1 and configured to rotate in contact with the first surface 30a, the recording method comprising a pattern forming step in which a first pattern of the liquid is formed on the first surface 30a by the liquid ejecting unit, and a detection region for the first pattern is formed at a specific position on the first surface 30a with which the roller is brought into contact when a rotational angle of the roller becomes $m^\circ + 360^\circ$, m° being a rotational angle of the roller when the roller is brought into contact with the first pattern.

The shapes of various patterns, that is, the first pattern, the second pattern, and the third pattern and the detection regions may be a shape other than a rectangular shape, for example, a circular shape, an elliptical shape or other shapes.

What is claimed is:

1. A recording device comprising:
a liquid ejecting unit configured to eject liquid to a first surface of a medium transported in a transport direction;
a roller disposed downstream of the liquid ejecting unit in the transport direction and configured to rotate in contact with the first surface; and
a control unit, wherein
the control unit is configured to form a first pattern of the liquid on the first surface by controlling ejection of the liquid by the liquid ejecting unit, and to form a detection region for the first pattern at a specific position on the first surface with which the roller is brought into contact when a rotational angle of the roller becomes $m^\circ + 360^\circ$, m° being a rotational angle of the roller when the roller is brought into contact with the first pattern.

15

tion region for the first pattern at a specific position on the first surface with which the roller is brought into contact when a rotational angle of the roller becomes $m^{\circ} + 360^{\circ}$, m° being a rotational angle of the roller when the roller is brought into contact with the first pattern.

2. The recording device according to claim 1, wherein the control unit is configured to cause the liquid ejecting unit to record an indication of a concentration of the first pattern in a region of the first surface avoiding the first pattern in a width direction intersecting with the transport direction.

3. The recording device according to claim 1, wherein the control unit is configured to form, side by side, a plurality of the first patterns that differ from each other in concentration in the width direction intersecting with the transport direction.

4. The recording device according to claim 1, wherein the detection region is a non-recording region in which the liquid is not ejected from the liquid ejecting unit.

5. The recording device according to claim 1, wherein a second pattern having a color corresponding to a color complementary to a color of the first pattern is formed in the detection region by the liquid ejecting unit.

6. The recording device according to claim 1, wherein the control unit is configured to form a plurality of first patterns side by side in the transport direction in a region having a length corresponding to a circumference of the roller in the transport direction of the medium, the plurality of first patterns each having a length, in the transport direction, corresponding to a value obtained by dividing the circumference by a positive integer n , and the plurality of first patterns being different from each other in concentration, and to form the detection region having a length in the transport direction corresponding to a length of the first pattern

5

30

16

at each of a plurality of the specific positions respectively corresponding to the plurality of first patterns.

7. The recording device according to claim 6, wherein the integer n is an odd number.

8. The recording device according to claim 6, wherein the control unit is configured to form the plurality of the first patterns such that the concentration of the first patterns increases in a stepwise manner from downstream to upstream in the transport direction.

9. The recording device according to claim 6, wherein the control unit is configured to include, among the plurality of the first patterns, a first pattern having a concentration at a preset maximum value.

10. The recording device according to claim 6, wherein the control unit is configured to form a third pattern in a region between the detection region located most upstream in the transport direction of the first surface and the detection region located second most upstream succeeding to the detection region located most upstream by controlling ejection of the liquid by the liquid ejecting unit.

11. A recording method performed by a recording device that includes a liquid ejecting unit configured to eject liquid to a first surface of a medium transported in a transport direction, and a roller disposed downstream of the liquid ejecting unit in the transport direction and configured to rotate in contact with the first surface, the recording method comprising a pattern forming step in which a first pattern of the liquid is formed on the first surface by the liquid ejecting unit, and a detection region for the first pattern is formed at a specific position on the first surface with which the roller is brought into contact when a rotational angle of the roller becomes $m^{\circ} + 360^{\circ}$, m° being a rotational angle of the roller when the roller is brought into contact with the first pattern.
